UNITED STATES PATENT OFFICE.

WILLIAM H. CONNELL, OF WILMINGTON, DELAWARE.

RAIL-JOINT.

SPECIFICATION forming part of Letters Patent No. 439,119, dated October 28, 1890.

Application filed April 25, 1890. Serial No. 349,413. (No model.)

To all whom it may concern:

Be it known that I, WILLIAM H. CONNELL, of Wilmington, county of New Castle, State of Delaware, have invented a certain new and 5 useful Improved Rail-Joint, of which the following is a true and exact description, reference being had to the accompanying drawings, which form a part of this specification.

My invention relates to the construction of 10 rail-joints, and my object is to provide an improved device for supporting the ends of the rails and preserving their vertical alignment or surface.

In an application for Letters Patent already 15 filed by me on the 3d day of February, 1890, and bearing the Serial No. 339,039, I have shown and described a rail-joint of very similar character to my present improvement, the leading feature of which consisted in the provision of projecting lugs at or near the ends 20 of the fish-plates, and which lugs were used to support a truss which in turn supported the rail-joint.

The object of my present invention is to 25 make my improved joint independent of particular construction of the fish-plates, and adapted for use with fish-plates already in service, so that it can be applied to old joints as well as new.

30 The nature of my improvement will be best understood as described in connection with the drawings, in which it is illustrated, and in which—

Figure 1 is an elevation of my improved 35 rail-joint; Fig. 2, a plan view thereof; Figs. 3, 5, and 7, elevations of various modifications of my joint; and Figs. 4, 6, and 8, plan views of the respective modifications, Fig. 4 being a view on the section-line $x-x$ of Fig. 3, and 40 Fig. 6 a view on the section-line $y-y$ of Fig. 5.

A A are the abutting ends of the rail.

B B are the fish-plates, which in the various 45 views are shown as of different lengths. Those in Figs. 1, 2, 7, and 8 are long, terminating at the points indicated at b b. Those indicated in Figs. 3 and 4 are somewhat shorter, terminating at the points indicated at b' b', while those indicated in Figs. 5 and 6 are still shorter, terminating at b'' b''.

50 C C, &c., are tie-supporting plates having flanges c³ c⁴, by which they are bolted directly or indirectly to the web of the rail. By "indi-

rectly" I mean instead of resting against the web they may rest wholly or partly against the fish-plate. Between the flanges each of 55 the tie supporting plates C is provided with a perforated shoulder c, preferably formed by bending the metal, as indicated in the drawings, so as to provide a surface c' against which the bolt holding the tie-rod can rest. This 60 surface may be formed in an oblique plane, as shown in Figs. 1 to 6, or the surface may be formed in a vertical plane, as shown in Figs. 7 and 8, and a leveling-washer G used to provide the necessary oblique surface to 65 support the nut.

c² indicates the perforation through the shoulder formed in the plate C.

D D, &c., are bolts and nuts, such as are ordinarily used for securing fish-plates to the 70 rails.

As shown in Figs. 1 and 2, the tie-supports C rest against the fish-plates B and are secured to them at the front, which hold the fish-plates in place.

In Figs. 3 and 4 the flanges c³ of the tie-supporting plates C rest against and are secured to the fish-plates by the bolts passing through them; but the outer flanges c⁴ extend back of the fish-plates and rest directly against the 80 flange of the rail, to which they are secured by a bolt D, while in Figs. 5 and 6 the tie-supporting plates C have both of their flanges c³ and c⁴ resting against and secured to the flange of the rail, the inner flange c³ abutting 85 against the ends of the short fish-plate indicated in those figures.

E is a strut conveniently formed, as shown, of a short section of a rail, and which is placed directly beneath the rail-joints, while F F are 90 tie-rods adapted to pass through the perforations c² of the tie-supports C and beneath the strut E.

f f are bolts by which the ties F are drawn up, so as to press against the strut E and press 95 it in turn against the rail-joint.

The device as a whole forms a truss by which the vertical strains and shocks to which the joint is subjected are converted into horizontal strains taken up by the rails themselves or by the rails and fish-plates combined.

The advantages of my present invention are, as already indicated, that it requires no

special form of fish-plate to be used in connection with it, that it is applicable to joints to such as are now in use, and can thus be applied to old as well as new joints, and that it is more easily put together than a joint such as is indicated in my pending application above referred to. The supporting-plates C, being independent of the fish-plate, are easily slipped upon the tie-rod before it (the tie-rod) is secured in place and before the supporting-plates C are bolted to the rail.

Having now described my invention, what I claim as new, and desire to secure by Letters Patent, is—

15 1. As a new article of manufacture, the tie-supporting plate C, having a shoulder c pro-

jecting from it and perforated to permit the passage of a tie-rod through it and flanges $c^3 c^4$, adapted to rest upon and be secured to the side of a rail or fish-plate.

2. In a rail-joint, the combination of the strut E, placed beneath the joint, independent tie-supporting plates C C, &c., secured to the rails in pairs on each side of the joint, and tie-rods F F, extending beneath the rail and secured at each end to the plates C, all substantially as and for the purpose specified.

WM. H. CONNELL.
